W. M. MYERS.
PRESSURE REGULATOR FOR PNEUMATIC TIRES.
APPLICATION FILED MAY 15, 1916.

Patented July 30, 1918.

WITNESS:

R. Hamilton

INVENTOR.
William M. Myers,
BY
Warren O. House
His ATTORNEY

UNITED STATES PATENT OFFICE.

WILLIAM M. MYERS, OF ST. JOSEPH, MISSOURI.

PRESSURE-REGULATOR FOR PNEUMATIC TIRES.

1,273,905.

Specification of Letters Patent. Patented July 30, 1918.

Application filed May 15, 1916. Serial No. 97,572.

To all whom it may concern:

Be it known that I, WILLIAM M. MYERS, a citizen of the United States, residing at St. Joseph, in the county of Buchanan and State of Missouri, have invented a certain new and useful Improvement in Pressure-Regulators for Pneumatic Tires, of which the following is a specification.

My invention relates to improvements in pressure regulators for pneumatic tires.

One of the objects of my invention is to provide novel means for attaching the pressure regulator to the filling tube of a pneumatic tire so as to securely retain it so attached and to render its unauthorized removal from the filling tube difficult.

A further object of my invention is to provide novel means for holding the casing from turning on the filling tube.

Still another object of my invention is to provide novel means for sealing and retaining closed the joint between the casing and filling tube.

Another object of my invention is to provide locking means for securing the casing to the filling tube which permits an authorized person provided with a proper implement to readily remove the casing from the filling tube when occasion requires.

Other novel features of my invention are hereinafter fully described and claimed.

In the accompanying drawings which illustrate the preferred embodiment of my invention,

Figure 1 is a side elevation of my improved pressure regulator.

Fig. 2 is an enlarged view showing my improved regulator attached to a portion of a vehicle wheel, a portion of the device being shown in vertical section and a portion in side elevation.

Fig. 3 is a cross section on the line 3—3 of Fig. 2.

Fig. 4 is a cross section on the line 4—4 of Fig. 2.

Fig. 5 is a cross section on the line 5—5 of Fig. 2.

Fig. 6 is a cross section on the line 6—6 of Fig. 2.

Similar reference characters designate similar parts in the different views.

1 designates the base of the casing of my improved pressure regulator, said base being hollow and provided with an internally screw-threaded upper end in which is fitted the externally threaded lower end of a cap

2, which with the base 1 forms a chamber adapted to hold fluid, such as air, under pressure.

For sealing the joint between the base 1 and the cap 2, there is provided upon the upper end of the base 1 a packing ring 3, against which the cap 2 has a bearing, Fig. 2. The base 1 is adapted to receive therein at its lower end the usual nut 4 which is commonly mounted upon the ordinary externally threaded filling tube 5, which extends through the usual rim 6 upon the outer side of which is mounted the usual pneumatic tire 7, to which is attached in the usual manner the filling tube 5. The nut 4, as is the common practice, bears against the inner side of the rim 6, which is the upper side, as viewed in Fig. 2.

I provide suitable means for holding the base 1 from turning on the filling tube 5, said means comprising, preferably, a washer 8, Fig. 6, which is adapted to be mounted on the nut 4 and which has a non-circular hole 9 adapted to receive therethrough the filling tube 5, opposite sides of which, as shown in Fig. 6, are flattened. The washer 8 is thus held from rotating on the tube 5. To hold the base 1 from rotating, it is provided internally with a longitudinal groove 10, Fig. 2, in which is fitted a peripheral projection 11, Fig. 6, on the washer 8.

The upper side of the washer 8 has a bearing against the under side of an internal annular flange 12 with which the base 1 adjacent to its lower end is provided. The filling tube 5 extends upwardly into the base 1 and cap 2 and is encircled by the annular flange 12.

For holding the base 1 from upward movement on the tube 5, and for sealing the joint between said tube and the base 1, to prevent escape of the compressed air held in the casing chamber, the following described means may be employed.

Mounted on the upper side of the annular flange 12, is a packing ring 13, Fig. 2, which tightly embraces the tube 5.

Mounted on the packing ring 13, is a collar 14, Fig. 4, preferably provided with a non-circular hole 15, through which the tube 5 extends, the size and shape of the hole 15, being such as to prevent rotation of the washer on the tube.

Mounted on the washer 14 is a nut 16 which is fitted upon the threaded tube 5, and which, through the intermediacy of the

washer 14 holds the packing ring 13 tightly compressed against the flange 12, and which also holds the casing from any upward movement on the tube 5.

5 In order that the nut 16 may not be readily turned, upon the removal of the cap 2, by an unauthorized person not provided with a proper implement, the nut has a diameter only slightly less than the interior 10 diameter of that portion of the base 1 in which the nut is located.

The upper side of the nut 16 may be provided with two diametrically opposite radial slots 17 which are adapted to receive a suitable key, not shown. Upon removing the cap 2 and employing a key or other implement of a proper shape, the nut 16 may be removed from the filling tube 5, after which the base 1, washer 14 and packing ring 13 20 may be vertically slipped off from the tube 5.

My improved regulator is adapted to be applied to the conventional type of filling tube 5, such as is shown in Fig. 2, and which is provided with the usual annular valve seat 18, against the under side of which is adapted to bear a valve 19, which, when used, is held seated by a coil spring 20.

The valve 19 is provided with the usual upwardly extending stem 21, which extends 30 through the valve seat 18, and which is normally held depressed with the valve 19 in the open position by a member 22 having arms 23 which engage the threaded periphery of the upper portion of the tube 5. By 35 means of this construction, a normally open air passage is provided between the tire 7 and the interior of the casing of my improved regulator.

To apply my improved regulator to a vehicle wheel, having a pneumatic tire provided with a filling tube of the kind illustrated, the washer 8 is slipped on the filling tube 5 so as to rest against the nut 4. The base 1, with the cap 2 removed, is then 45 slipped over the filling tube to a position in which the washer 8 will bear against the under side of the flange 12, and the projection 11 will be in the groove 10.

The packing ring 13 and the washer 14 50 are then slipped, in the order named, upon the tube 5, following which the nut 16 is screwed onto the tube 5 and to a position in which the packing ring 13 will bear tightly against the flange 12. The member 22 is 55 then applied to the filling tube 5 in a position such that it will hold the valve 19 open, as shown in Fig. 2. The cap 2 is then screwed into the base 1 tightly against the packing ring 3.

60 As thus assembled, the base 1 cannot be intentionally or accidentally turned on the tube 5, and the unauthorized removal of the regulator is rendered difficult, due to the fact that the locking parts are all in the interior of the casing, and in order to remove

the device, the cap 2 must be first removed, and the nut 16 unscrewed with a suitable implement designed for the purpose.

The locking means serves not only to lock the casing to the filling tube, but it also 70 serves to tightly seal the joint between the filling tube and the casing.

I do not limit my invention to the structure shown and described, as modifications, within the scope of the appended claims, 75 may be made without departing from the spirit of my invention.

What I claim is:—

1. In a pressure regulator for pneumatic tires, a casing adapted to be slipped over the filling tube of a tire, and means engaging the casing and adapted to interlock with and non-rotatably engage said filling tube for locking the casing to the filling tube and for holding it from rotation thereupon. 80

2. In a pressure regulator for pneumatic tires, a casing adapted to be slipped over the filling tube of a tire, and means located within the casing and engaging therewith and adapted to interlock with and non-rotatably engage said filling tube for locking the casing to the filling tube and for holding it from rotation thereupon. 90

3. In a pressure regulator for pneumatic tires, a casing adapted to be slipped over the filling tube of a tire, the filling tube being non-circular in cross section, and means including a washer for engaging the casing and adapted to engage the filling tube, to prevent rotation of the casing on the filling tube, the washer having means for engaging the casing and filling tube in a manner such that the washer will be held from rotation relative to the casing and the filling tube. 95

4. In a pressure regulator for pneumatic tires, a casing adapted to be slipped over the filling tube of a tire, the filling tube being non-circular in cross section, means for holding the casing from longitudinal movement on the filling tube, and a washer having an opening adapted to receive the filling tube, said opening being of a size and shape such that the washer is held from rotation on the filling tube, the washer having means for interlocking with the casing for holding the latter against rotation relative to the washer. 105

5. In a pressure regulator for pneumatic tires, a casing adapted to be slipped over the filling tube of a tire, means located within the casing and adapted to engage said filling tube for holding the casing from longitudinal movement on the filling tube, and means within the casing and engaging the same and adapted to engage said filling tube 110 non-rotatably for holding the casing against rotation on the filling tube. 120

6. In a pressure regulator for pneumatic tires, a casing adapted to be slipped over the filling tube of a tire, a washer adapted 115

to slip over said filling tube and having means for having non-rotatable engagement with the filling tube and with the casing, a second washer adapted to be slipped over the filling tube and having means for having non-rotatable engagement with the filling tube, the casing having a portion disposed between said two washers, and releasable means adapted to engage the filling tube and the second washer for holding the latter from longitudinal movement on the filling tube.

7. In a pressure regulator for pneumatic tires, a casing comprising a base adapted to be slipped over a filling tube of a tire and a cap removably engaging said base, the base having an internal annular flange adapted to encircle the filling tube, the base having also a longitudinal groove, a washer adapted to slip over said filling tube and having means for non-rotatably engaging said tube and provided with a projection adapted to fit in said groove, the washer having a bearing against the under side of said flange, and means adapted to slip over said tube and to have engagement therewith and adapted to engage the upper side of said flange for holding the base from upward movement on said tube.

8. In a pressure regulator for pneumatic tires, a casing comprising a base having an internal annular flange adapted to slip over the filling tube of a tire and a cap removably fitted to the base, a washer having a bearing against the under side of said flange and having means for non-rotatably engaging the filling tube and base, a packing ring adapted to encircle the filling tube and having a bearing against the upper side of said flange, a second washer adapted to encircle the filling tube and having a bearing against the upper side of said packing ring, and a nut adapted to have threaded connection with the filling tube and having a bearing against the second washer.

9. In a pressure regulator for pneumatic tires, a casing having a base provided with an annular internal flange adapted to slip over the filling tube of a tire and having below the flange a longitudinal groove, a washer having means for non-rotatably engaging the filling tube and having a projection fitted in said groove and adapted to bear against the under side of said flange, packing means encircling the filling tube and bearing against the upper side of said washer, and releasable means for holding the packing means against said flange and having means adapted to engage the filling tube.

10. In a pressure regulator for pneumatic tires, a casing having a base provided with an annular flange adapted to slip over the

filling tube of a tire, a locking member having means adapted to non-rotatably engage the filling tube and the base for holding the latter from rotation on the tube, packing means adapted to encircle the filling tube and having a bearing against the upper side of the flange, and releasable means adapted to engage the filling tube for holding the packing means against the flange.

11. In a pressure regulator for pneumatic tires, a casing having a base provided with an internal annular flange adapted to slip over an externally threaded filling tube of a tire, locking means adapted to non-rotatably engage the tube and base, packing means adapted to encircle the tube and having a bearing against the upper side of said flange, and a nut adapted to be fitted on said tube and bearing against the packing means.

12. In a pressure regulator for pneumatic tires, a casing having a base provided with an internal annular flange adapted to slip over an externally threaded filling tube of a tire, the base having below the flange a longitudinal groove, a washer adapted to slip over the tube and having means for non-rotatably engaging the tube and having a projection fitted in said groove and bearing against the under side of said flange, a packing ring adapted to encircle the tube and bearing against the upper side of said flange, a washer bearing upon said packing ring, and a nut adapted to be fitted on said filling tube and bearing upon the second named washer.

13. In a pressure regulator for pneumatic tires, a casing having means for holding fluid under pressure and adapted to be slipped over the filling tube of a tire, means adapted to non-rotatably engage the filling tube and the casing for holding the latter from turning on the filling tube, and means within the casing for engaging the casing and adapted to engage the tube for holding the casing from longitudinal movement on the tube.

14. In a pressure regulator for pneumatic tires, a casing having means for holding fluid under pressure and adapted to be slipped over the filling tube of a tire, means adapted to non-rotatably engage the filling tube and the casing for holding the latter from turning on the tube, packing means adapted to close the joint between the tube and casing, and means adapted to engage the filling tube and the packing means for holding the casing from longitudinal movement on the tube and for retaining the packing means in operative position.

In testimony whereof I have signed my name to this specification.

WILLIAM M. MYERS.
